UNITED STATES PATENT OFFICE

2,602,403

RATCHET PAWL MECHANISM FOR RAILWAY
DUMP CARS

George B. Dorey, Westmont, Quebec, Canada, assignor to Enterprise Railway Equipment Company, Chicago, Ill., a corporation of Illinois

Application September 12, 1949, Serial No. 115,137

4 Claims. (Cl. 105—312)

1

This invention relates, generally, to ratchet pawl mechanisms for railway dump cars, and it has particular relation to biasing means therefor.

Among the objects of this invention are: To provide for biasing a pawl on each side of a railway car into engagement with a ratchet operating mechanism on each side which controls the simultaneous operation of the center doors, the biasing effect being obtained substantially without the addition of weight to the pawls or the means mounting or actuating the same; and to mount the pawls for rotation with a transversely extending shaft and to deform the shaft in such manner as to provide the desired biasing action.

Other objects of this invention will, in part, be obvious and in part appear hereinafter.

This invention is disclosed in the embodiment thereof shown in the accompanying drawings and it comprises the features of construction, combination of elements and arrangement of parts which will be exemplified in the construction hereinafter set forth and the scope of the application of which will be indicated in the appended claims.

For a more complete understanding of the nature and scope of this invention, reference can be had to the following description, taken together with the accompanying drawings, in which:

Figure 1 is a top plan view taken generally along the line 1—1 of Figure 4 showing a portion of the two operating mechanisms for the two sets of center doors of a railway dump car;

Figure 2 is a view, partly in longitudinal section and partly in side elevation, showing the arrangement of the centrally located floor of a railway dump car, the floor being arranged to slope in opposite directions from the center of the car toward the dump doors located on each side of the center;

Figure 3 is a view in side elevation taken along the line 3—3 of Figure 1 and looking in the direction of the arrows; and

Figure 4 is a transverse cross-sectional view taken along the line 4—4 of Figure 2.

Figure 5 is a plan view of the transverse shaft carrying the ratchet wheels and the parallel transverse shaft carrying the pawls for engaging the ratchet wheels, the latter shaft having the offset portion for biasing the pawls into operative engagement with the ratchet wheels.

Referring now particularly to Figures 1, 2 and 4 of the drawings, it will be observed that center doors 10 are illustrated having complementary

2

side doors 11. The doors 10 and 11 are hinged on longitudinally extending shafts 12 which are located on opposite sides of a center sill 13 which extends longitudinally of the car. It will be understood that there may be four sets of center and side doors 10 and 11, each set being located at the bottom of a pocket. The pockets are defined by longitudinally sloping floors 14 and 15 and transversely sloping floors 16. As shown in Figure 2 the longitudinally sloping floors 14 are inclined from the transverse center of the car toward the pockets at the ends while the sloping floors 15, only one being shown, are inclined from the ends of the car toward the pockets. Side walls 17, Figure 4, extend upwardly from the sloping floors 16 as indicated.

In order to control the movement of the side doors 11 chains 20 are provided. The chains 20 are arranged to extend over sheaves 21 which are fast on winding shafts 22 which extend along the sides of the car. Each of the winding shafts 22 is provided with a worm and a gear mechanism 23, Figure 1, for rotating the same. An operating handle 24 is associated with each of the worm and gear mechanisms 23 and its position is controlled, in part, by a pawl 25. It will be understood that each of the side doors 11 is operated individually by its worm and gear mechanism 23 under the control of the operating means 34.

Now it is desirable that the center doors 10 of each pair of pockets be operated simultaneously. For this purpose chains 28 are provided and they extend over idler pulleys 29, Figure 4, and sheaves 30 which are fast on winding shafts 31. Since there are four pockets, two winding shafts 31 are provided as illustrated in Figure 1. Also as here shown a worm and gear mechanism 32 is arranged to rotate the winding shaft 31. The worm and gear mechanism 32 is located underneath the railway car in alignment with the winding shaft 31.

It is desirable that the worm and gear mechanism 32 be operated from either side of the car and for this purpose a transverse shaft 33 is provided. It will be understood that there are two transverse shafts 33, as shown in Figure 1, and that they extend from one side of the car to the other. At each end of each transverse shaft 33 operating means, shown generally at 34, is provided.

The operating means 34 is shown in more detail in Figure 3 of the drawings. It comprises a casting having four arms 35 which are spaced ninety degrees apart and each has a socket 36 therein

for receiving an operating bar. When the operating means 34, which is fast on the outer end of each shaft 33, is rotated in the direction indicated by the arrow 37 the doors 10 are permitted to open. When the operating means 34 is rotated in the opposite direction as indicated by the arrow 38, the corresponding center doors 10 are swung to the closed position.

With a view to holding the operating means 34 in any position to which it may be rotated and principally to hold the center doors 10 in the closed position, pawls 41 are provided, there being a pawl 41 for each of the operating means 34. It will be observed that each pawl 41 is arranged to interfit between the arms 35 of the associated operating means 34 so as to hold the same in position. It will be understood that there is a pawl 41 at each side of the railway car for holding the operating means 34 thereat in position. When it is desired to move the center doors 10 from one position to another, it is necessary to move both of the pawls 41 out of engagement with the operating means at each end of the transverse shaft 33. For this purpose the pawls 41 are located on the ends of transverse shafts 42 which extend from side to side of the car, there being a shaft 42 for each of the transverse shafts 33 and extending parallel thereto and underneath the longitudinally sloping floors 14 as shown more clearly in Figure 2. The pawls 41 may be secured non-rotatably to the ends of the shafts 42 by any suitable means such as by pins 43. Bearing brackets 44, suitably carried on the underside of the car frame serve to rotatably support the transverse shafts 42 in operative position.

It is desirable that the pawls 41 be biased either to operative position with respect to the associated operating means 34 or that they be biased entirely away therefrom. In the past it has been the practice to provide a separate arm in the form of a counterweight for accomplishing this purpose. Springs also have been used.

In accordance with the present invention, in lieu of providing a separate counterweight or a spring, each of the transverse shafts 42 on which the pawls 41 are mounted is deformed as indicated at 45 intermediate its ends, the deformation being substantially in the plane containing the pawls 41. This offset portion 45 of each of the transverse shafts 42 inherently acts as a counterweight and serves to bias the pawls 41 into operative engagement with the operating means 34 or, when the pawls 41 are moved out of such operative engagement, the offset portion 45 serves to bias the pawls 41 away therefrom.

Since only a slight amount of additional material is required for each of the transverse shafts 42 when the offset portion 45 is provided therein, there is substantially no increase in weight required to provide the biasing means. Further, the offset portion 45 can be positioned underneath the sloping floors 14 and thus requires a minimum of space.

Since certain changes can be made in the foregoing construction and different embodiments of the invention can be made without departing from the spirit and scope thereof, it is intended that all matter shown in the accompanying drawings and described hereinbefore

shall be interpreted as illustrative and not in a limiting sense.

What is claimed as new is:

1. In a latching mechanism for railway dump car doors having operating means on opposite sides for controlling the operation thereof from either side, in combination, a pair of pawls on said opposite sides of said car cooperating with said operating means to restrain the same and hold said doors closed, and a shaft rotatably mounted transversely of said car and having said pawls non-rotatably connected thereto, an intermediate section of said shaft being offset from its axis of rotation to bias said pawls to predetermined position.
2. In a latching mechanism for railway dump car doors having operating means on opposite sides for controlling the operation thereof from either side, in combination, a pair of pawls on said opposite sides of said car cooperating with said operating means to restrain the same and hold said doors closed, and a shaft rotatably mounted transversely of said car and having said pawls non-rotatably connected thereto, an intermediate section of said shaft being offset from its axis of rotation in the direction that said pawls extend therefrom to bias them into engagement with said operating means.
3. In a latching mechanism for railway dump car doors having operating means on opposite sides for controlling the operation thereof from either side, in combination, a pair of pawls on said opposite sides of said car cooperating with said operating means to restrain the same and hold said doors closed, and a shaft rotatably mounted transversely of said car and having said pawls non-rotatably connected thereto, a portion of said shaft between said pawls being offset laterally in the plane of said pawls and cooperating therewith in one position to bias them into engagement with said operating means and in another position to bias them to a non-engaging position.
4. In a latching mechanism for railway dump car doors extending longitudinally from a transversely extending sloping floor and having operating means on opposite sides for controlling the operation thereof from either side, in combination, a shaft, bearings at opposite sides of said car rotatably supporting said shaft underneath said sloping floor, and pawls fast on the ends of said shaft cooperating with said operating means to restrain the same and hold said doors closed, an intermediate section of said shaft beneath said sloping floor being offset from its axis of rotation to bias said pawls to predetermined position.

GEORGE B. DOREY.
